J. T. LANDGRAF

BAFFLE FOR COAL BURNING HEATERS

Filed Jan. 23, 1928

UNITED STATES PATENT OFFICE.

JACOB T. LANDGRAF, OF MACOMB, ILLINOIS, ASSIGNOR TO AMERICAN STEEL PRODUCTS CO., OF MACOMB, ILLINOIS, A CORPORATION OF ILLINOIS.

BAFFLE FOR COAL-BURNING HEATERS.

Application filed January 23, 1928. Serial No. 246,615.

My invention relates to stoves or heaters for use with solid fuel, and more particularly to the class of such heaters in which the normal draft up the flue is retarded by the intermediate position of a check-draft chamber or other baffle arrangement between the combustion chamber of the heater and the flue.

When heaters of this class are used with some kinds of fuel, such as cheap grades of soft coal, certain constituents of the combustion gases will condense in the flue pipe to form a more or less sticky liquid which drops down into the heater and collects on any baffle portion that may underhang the flue pipe,

while the relatively cooler walls of the flue pipe also collect soot which drops down into the heater. The resulting combination of soot with tarry or otherwise viscous deposits forms a sticky accumulation which gradually clogs the passages leading from the combustion chamber of the heater into such a draft chamber, thereby interfering with the effective operation of the heater. This interference has proven particularly serious with heaters in which the walls of the baffle chamber or check-draft chamber are cast integral with the stove body, since the interior of the chamber is not readily accessible for removing such deposits.

My present invention aims to overcome these difficulties by providing a heater in which a readily removable and easily cleaned baffle member cooperates with wall portions of the heater body to form such a check-draft chamber, and in which the baffle member is constructed so that it cannot be dropped accidentally into the interior of the heater body. It also provides a heater construction for this purpose, which can readily be built in a simple flat topped form with very little coring in the castings, which will insure a safe attaching of the baffle member to the body, which will readily permit the substitution of differently formed baffle members suited to various types of fuels, and which can be employed equally well with different shapes of stove bodies. Moreover, my invention provides a heater of this class in which the passages connecting the combustion chamber of the heater with the check-draft chamber can readily be adjusted in size.

Furthermore, my invention provides a baffle member which affords a check-draft chamber within the heater and which can readily be employed with a damper-controlled inlet

to the check-draft chamber without requiring a separate top casting or complicated provisions for supporting the baffle member. Still further and also more detailed objects will appear from the following specification and from the accompanying drawings, in which

Fig. 1 is a central and vertical section through the upper portion of a heater embodying my invention and including a damper-controlled check-draft inlet and a damper adjustably controlling the upward passage of combustion gases through the baffle member.

Fig. 2 is a fragmentary rear view, taken from the line 2--2 of Fig. 1.

Fig. 3 is a horizontal section taken along the line 3--3 of Fig. 1.

Fig. 4 is a perspective view of the baffle member shown in Figs. 1 to 3.

Fig. 5 is a vertical section through the upper portion of another heater embodying my invention, namely one having no inlet for admitting fresh air to the check-draft chamber and having no adjustable control of the restriction of the gas passage by the baffle member, and also having different arrangements for supporting the baffle member.

Fig. 6 is a perspective view of the baffle member of Fig. 5.

Fig. 7 is a perspective view of another form of baffle member suitable for use with the heater body of Fig. 1, namely one having no adjustable control of the combustion gases passing from the combustion chamber to the flue.

Referring first to the embodiment of Figs. 1 to 3, these figures show a heater body 1 having an upper fuel inlet normally closed by a lid 2 and an upper flue collar 3 supporting the usual flue pipe 4. To restrict the rate at which the gases of combustion pass from the interior of the upper part of the heater body (which is the combustion chamber 7 of the heater), I provide a baffle member constructed as shown separately in Fig. 4. This includes a baffle bottom 5 which underhangs the flue collar and which may have its ends close to the adjacent sides of the heater body 1, and a riser web 6 extending between the effective fuel inlet and the flue. When supported as in Fig. 1, this baffle member co-operates with the side, rear and top walls of the heater body to form a check-draft chamber 17 underhanging the flue, through which chamber the gases of combustion must go in passing from the combustion chamber 7 to the flue collar 3.

To admit the gases to this chamber I provide one or more passages and preferably dispose at least a portion of these passages in the baffle bottom 5 and directly under the flue. I also desirably provide means for adjustably controlling the total effective size of such passages, so that the rate of gas flow can be controlled within the heater in proportion to the nature of the fuel, the barometrically affected flue draft, and the room temperature. Illustrative of such a control arrangement, Figs. 3 and 4 show the baffle bottom as having two sector-shaped apertures 8 controlled by a damper 9 which is rotatably mounted on the baffle bottom and which has similarly shaped apertures 10 adapted to be brought more or less into alignment with the baffle bottom apertures 8.

To support the baffle member in its above described operative position I preferably provide spaced means for supporting the free end of the baffle bottom 5 and the upper end of the riser (or partition-forming) part 6 from the heater body. In Figs. 1 and 3, this heater body is provided in its rear wall with a check-draft opening 11 controlled by a damper, which may be automatically operated after the manner shown in application No. 226,652 of William Dow Harvey, filed October 17, 1927, on a coal-burning brooder. Where such a check-draft opening is provided at the opposite edge of the baffle bottom from the riser web 6, I preferably make the baffle bottom of such an effective length as to extend into the opening 11, so that the lower edge of this opening will support the free end of the baffle bottom. Since such a check-draft opening is usually of less width than the heater wall in which it is formed, I accomplish this by providing the baffle bottom 5 at its free end with an extension 13 projecting into the said opening. This extension preferably corresponds in width closely to that of the opening, so as to aid in centering the baffle member laterally of the heater body.

The other end of the baffle member is preferably supported exteriorly of the stove body and in such a manner as to deter an accidental dropping of the baffle member into the stove. For this purpose, I desirably make the riser web 6 of such a height as to fit snugly under the stove lid 2 and I provide this riser web adjacent to its upper edge with oppositely directed fingers 15 resting respectively on the upper ends of the two sides of the heater body 1. I also desirably provide means on the riser web whereby this can readily be gripped for raising it, such as the two-winged socket 16 of Figs. 1 and 3. With this arrangement for supporting the baffle member, I also preferably form the stove lid 2 with a portion engaging the face of the riser web which is directed away from the support for the free end of the baffle bottom, as

by providing the lid with a downwardly directed ledge 18. With the stove lid and heater top formed in any usual manner for definitely positioning the lid, such a ledge compels the user to slide the baffle member into its proper position (namely, with the free end of its bottom adequately supported in the aperture 11) before the lid can be set into its closure position, after which the lid holds the baffle member against sliding away from the heater wall which supports the free end of its bottom.

When the lid is removed, the baffle member can readily be withdrawn, particularly if provided with a socket as here shown. During its withdrawal, and also when replacing the baffle member, the projecting fingers 15 (which have their tips spaced by a greater distance than the interior width of the heater body at its top) prevent the baffle member from being dropped into the heater even with careless handling. When the baffle member is withdrawn from the heater body, the soot, flue drop and other deposits can easily be scraped off the same; and if a rotatable damper is employed as in Figs. 1 to 4, a rotation of this will shear off any deposits that may have gathered in the openings.

In practice, the baffle member need not have either its bottom or its riser web extend close to the walls of the heater body, as a part of the combustion gases and smoke may be allowed to pass between these walls and the edges of the baffle member. However, I have found that when any considerable spaces are left adjacent to the walls of the heater body, the deposits which collect there are much more difficult to detach than from a removable baffle member. For this reason, I preferably arrange the gas passage spaces so that at least the greater portion of the gases will pass through perforations in the baffle member, but I may leave spaces also adjacent to the walls of the heater body thereby keeping part of the hot gases closer to these walls.

However, I do not wish to be limited in this respect, nor to the particular supporting arrangements above described or to the use of my baffle member in a heater body having a lateral check draft opening. Many changes might obviously be made without departing either from the spirit of my invention or from the appended claims, and I also do not wish to be limited to the use of the various novel features of my invention in conjunction with one another.

Illustrative of other embodiments of my invention, Fig. 5 shows upper portions of a heater in which the check-draft chamber 17 has no inlet for air from outside the heater body 18'. In this case, the baffle member has spaced apertures 19 in its bottom 20, while the free end of this bottom is supported by a screw 21 extending through a wall of the heater body. The riser web 22 of the same

baffle member has its upper end recurved to form a hook 23 which hooks over a rib 24 on the top of the heater body, and the lid 25 in this case may be formed to fit over the hook formation 23.

Fig. 7 shows another baffle member suitable for use with the heater body of Figs. 1 and 2, but having no means for varying the size of the gas passages.

With baffle members of the types of Figs. 4 and 7, the heater body may have upwardly open notches, such as the notch 26 of Fig. 3 in which the fingers 15 are socketed, thereby permitting the upper end of the baffle member to be flush with the adjacent upper end portions of the heater body; as also shown by the notch 27 of Fig. 5. With the heater body thus formed, one riser wall of each notch engages the adjacent outer face of the adjacent finger to prevent the baffle member from sliding away from the flue opening.

In each of the illustrated constructions, it will be noted that no difficult coring is required for the heater body, that the main portion of the baffle member is an easily made casting, and that the heater can readily have the flat top which is particularly desirable in brooder stoves where a hoover is to be supported from the top. It will also be obvious that the position of the damper 9 can readily be adjusted whenever the baffle member is withdrawn from the heater. By using such a gas-passage controlling damper on an inner wall of the check-draft chamber, I can secure the desired control of the heat while retaining more of the heat within the heater body, thus also saving fuel.

I claim as my invention:

1. A coal burning heater comprising a body having a flue aperture and a fuel aperture in its top, and a baffle member adapted to be removed through the fuel aperture; the baffle member having an upper end projecting through the fuel aperture and supported by the upper end of the heater body, the baffle also having a lower portion supported by the said body at the opposite side of the flue aperture from its upper end, the said upper ends of the baffle member and the heater body having coacting portions which interengage to prevent the baffle member from sliding within the heater body toward the fuel aperture.

2. A coal burning heater comprising a body having a flue aperture and a fuel aperture in its top, and a baffle member adapted to be removed through the fuel aperture; the baffle member having an upper end supported by heater body adjacent to the fuel aperture and having a lower portion supported by the body at the opposite side of the flue aperture from its said upper end, and a lid normally closing the fuel inlet and overhanging the said upper end of the baffle member, the lid and the baffle member having interengaging

portions arranged to prevent the baffle member from sliding within the heater body toward the fuel aperture.

3. A coal burning heater comprising a body having a flue aperture in its top and a check-draft aperture in a lateral body wall near the flue aperture, and a baffle member disposed within the body; the baffle member comprising a riser web supported at its upper end by the top of the heater body, and a bottom having an edge portion resting on the lower edge of the check draft aperture, the body having a fuel aperture partially overhanging the upper end of the said upright web; in combination with a lid for the fuel inlet, the lid having a portion engaging the said upright web to prevent movement of the baffle member away from the flue aperture.

4. In a coal burning heater, a body having a check-draft aperture in a side wall thereof near the top of the heater, the body also having a flue opening adjacent to the said aperture and a fuel opening on the opposite side of the flue opening from the check-draft aperture; and a baffle member having its main portions disposed within the body and adapted to be removed through the fuel opening; the baffle member comprising a riser web extending between the flue opening and the fuel opening, and a bottom extending from the lower end of the riser web to the said side wall, the said bottom projecting at its free end into the side wall aperture and resting on the lower edge of that aperture; the upper end of the body having a ledge portion underhanging an upper end portion of the baffle member, whereby the said ledge portion and the lower edge of the check-draft aperture co-operate in supporting the baffle and whereby the baffle member cooperates with adjacent parts of the heater in forming a check draft chamber connecting the flue with the said aperture; and means engaging the upper end of the baffle member to prevent movement of the latter away from the check-draft aperture.

5. In a coal burning heater, a body having a flue aperture and a fuel opening in its top and having an upwardly open notch in the upper edge of each of two opposite side walls and adjacent to the fuel opening; and a baffle member comprising a bottom underhanging the flue aperture and a riser web extending upward from one end of the horizontal web adjacent to the fuel opening, the riser web having two projections normally seated respectively on the bottoms of the said notches, and the heater body having a ledge supporting a part of the baffle member spaced from the said vertical web; the said riser web extending near to the side walls of the heater body and the horizontal web having portions cut away to provide gas passages through it.

6. In a coal burning heater, a body member comprising a body having a flue aperture and a fuel opening in its top and a lid for the

fuel opening; and a baffle member disposed within the heater body and having its main portion adapted to be withdrawn through the fuel opening, the baffle member comprising a bottom and a riser web extending upwardly from one edge of the said bottom through the fuel opening and adjacent to the flue opening; the body having two horizontally spaced portions cooperating to support the baffle member in its said disposition, the body member having two portions normally engaging opposite faces of the said riser web to prevent horizontal movement of the baffle member towards or away from the flue opening.

7. A coal burning heater comprising a body having a flue aperture and a fuel opening in its top and having a check-draft aperture in a lateral body wall near the flue aperture; a baffle member normally disposed within the body and comprising a riser web supported at its upper end by the top of the heater body, and a horizontal web having an edge portion supported by the said body wall, one of the said webs having an opening for the passage of combustion gases through it; and a control member disposed entirely within the heater body and adjustably mounted on the last named web for controlling the effective size of the said passage, the control member having a portion disposed for cooperating with walls of the said passage to shear off deposits which have collected in the passage.

8. In a coal burning heater, a body including sides and a top, the body being provided in its upper portion with a flue opening and a check-draft aperture; a baffle member removably supported within the body and including a bottom web underhanging the flue opening and a riser web, the said webs extending

close to two sides and the top of the body and coacting with the said sides and body to form a chamber under the flue opening, the bottom web having passages through it forming the sole connection between the said chamber and the combustion chamber of the heater; and a damper rotatably mounted on the bottom web for controlling the said passages, the damper having edge portions adapted to cooperate with edges of the said passages for shearing off deposits which have collected in the said passages.

9. A coal burning heater including a body member having a flue aperture in its top; a baffle member removably supported within the body member and cooperating with parts of the body member to afford a check-draft chamber below the flue aperture and above the combustion chamber of the heater; the baffle member having a portion underhanging the flue aperture and formed to provide one or more passage ways affording the major connection for the flow of combustion gases from the combustion chamber to the check-draft chamber; and a damper disposed entirely within said check-draft chamber and movably mounted on the baffle member for adjustably controlling the flow of combustion gases through a passageway; the heater having a movably mounted exterior portion through which the baffle member can be withdrawn to permit the detaching of deposits from the baffle member, the arrangement being such that the baffle member when within the heater must be in its normal position before the said exterior portion can be moved to its normal position.

Signed at Macomb, Illinois, January 20th, 1928.

JACOB T. LANDGRAF.
